UNITED STATES PATENT OFFICE.

GEORGE FERGUSON, OF MORAVIA, NEW YORK.

DESIGN FOR A CASKET OR BURIAL-CASE.

SPECIFICATION forming part of Design No. 12,880, dated April 11, 1882.

Application filed March 2, 1882. Term of patent 14 years.

To all whom it may concern:

Be it known that I, GEORGE FERGUSON, a citizen of the United States, and resident of Moravia, in the county of Cayuga and State of New York, have invented a new and valuable Design for Caskets, Burial-Cases, &c.; and I do hereby declare that the following is a full, clear, and exact description of the construction and operation of the same, reference being had 10 to the annexed drawings, making a part of this specification, and to the letters and figures of reference marked thereon.

Figure 1 of the drawings is a representation of a perspective view of the burial case, showing the design; and Fig. 2 is a plan view of the same.

This design relates to the form or configuration of caskets or burial-cases; and it consists in shaping the case with side projections, forming the walls of the arm-recesses and re-entrant angles at each end of said projections. The general design in plan is that of a cross, the head portion being represented at *a*, the foot at *b*, and the side projections or arms at 25 *c c*. The side projections, *c c*, are connected to the head and foot portions by the side walls, *d*, which form re-entrant angles, as indicated at *e*, exteriorly, while within the case corre-

sponding projections of angular form, *g*, appear. The side projections, *c c*, form recesses, 30 within which the arms are designed to rest. Their length is usually about sixteen inches and the distance between their outer walls twenty inches. The head and foot portions are about twelve inches across near their ends, and 35 are usually finished with beveled corners, the entire design being that represented in the drawings.

Coffins have been shaped to conform nearly to the shape of the human form; but such a 40 configuration is not broadly claimed herein.

What I claim and desire to secure is—

The design for caskets or burial-cases, the same consisting of a cross-shaped case having the arm-projections *c c* at the sides and the 45 re-entrant angles *e e* at the ends of said arm-projections where they join the walls of the head and foot portions, as shown.

In testimony that I claim the above I have hereunto subscribed my name in the presence 50 of two witnesses.

GEORGE FERGUSON.
